UNITED STATES PATENT OFFICE.

JOHN T. HUCK, OF SAN FRANCISCO, CALIFORNIA, ASSIGNOR OF ONE-HALF TO WARREN J. FLICK, OF SAN FRANCISCO, CALIFORNIA.

RATCHET MECHANISM.

1,142,574.

Specification of Letters Patent. Patented June 8, 1915.

Application filed February 4, 1914. Serial No. 816,492.

To all whom it may concern:

Be it known that I, JOHN T. HUCK, a citizen of the United States, residing at San Francisco, in the county of San Francisco 5 and State of California, have invented new and useful Improvements in Ratchet Mechanism, of which the following is a specification.

This invention relates to improvements 10 in ratchet mechanisms and has particular application to ratchet mechanism of the roller type.

In carrying out the present invention, it is my purpose to provide a ratchet mechanism 15 of the class described whereby an effective and efficient connection will be formed between the driving member and the driven member when the former is rotated in one direction and whereby the driver may run 20 idle, when rotated in the opposite direction, with the least possible friction between the parts.

It is also my purpose to provide a mechanism of the type set forth which will embrace the desired features of simplicity, efficiency and durability, one which may be installed and maintained at a minimum expense and one which may be manufactured and marketed at small cost.

30 With the above and other objects in view, the invention consists in the construction, combination and arrangement of parts hereinafter set forth in and falling within the scope of the claim.

35 In the accompanying drawings; Figure 1 is a view in front elevation of a ratchet mechanism constructed in accordance with my present invention. Fig. 2 is a vertical transverse sectional view therethrough. 40 Fig. 3 is a similar view taken at right angles to Fig. 2. Fig. 4 is a collective view showing parts of the mechanism in elevation.

Referring now to the drawings in detail, 1 designates the driving member of the 45 ratchet mechanism, such member comprising a disk 2 having a central opening 3 formed therein and provided with an outwardly extending annular collar 4 concentrically of the opening, such collar being 50 preferably formed integral with the disk and is equipped with a set screw 5 by means of which the disk may be fastened to a shaft or other like element. Formed on the periphery of the disk 2 is an annular flange 6. 55 Disposed within the flange 6 and in con-

tact therewith is an annulus 7 having the inner wall thereof formed with a series of pockets 8 having inclined inner walls 9 terminating at the relatively deep ends thereof in abrupt shoulders 10. Formed in the annulus 7 and leading from the shoulders 10 onto the periphery of such annulus are angularly arranged bores 11 alining with threaded apertures 12 formed in the flange 6 and disposed at an angle thereto. Slidably mounted within each bore 11 is a shoe 14 having the inner end thereof concaved as at 15 and adapted to project into the adjacent pocket, and connected with the outer end of the shoe is a pin 16, while threadedly engaging each aperture 12 is a plug 17 designed to hold the shoe within the bore. A coiled expansion spring 18 surrounds each pin 16 and has one end abutting the outer end of the shoe and the opposite 75 extremity in engagement with the inner end of the plug 17, such spring acting to force the shoes normally into the respective pockets.

19 designates the driven member of the 80 ratchet mechanism, such member comprising an annular plate 20 disposed within the annulus 7 and formed with a central opening coaxial with the opening 3 in the disk 1. Connected with the plate 20 or formed integral therewith and extending outwardly therefrom is a collar 21 adapted to be connected with a shaft or other mechanism to be driven from the ratchet mechanism. The periphery of the plate 20 is spaced apart a 85 slight distance from the inner wall of the annulus 7 formed with the pockets 8 and disposed within such pockets are rollers 21' engaging the inner inclined walls of the respective pockets and the periphery of the 90 annular plate. In the present instance, a ring-like plate 23 is fastened to the outer edge of the flange 6 and acts to prevent accidental displacement of the rollers 21.

95 From the foregoing description taken in connection with the accompanying drawings, the construction, mode of operation and manner of employing my invention will be readily apparent. It will be seen that when the driving member 1 of the clutch or ratchet mechanism is rotated in the direction of the arrow in Fig. 1 the rollers will 100 be caused to bind between the inclined inner walls of the pockets and the periphery of the plate 20 of the driven member thereby 105 110

effecting a connection between the driving and driven members to rotate the latter from the former. On the other hand, when the direction of rotation of the driving member is reversed the rollers ride into engagement with the shoulders 10 of the pockets thereby permitting the driving member to idle over the member 19 of the ratchet mechanism. When the driving member is rotated 10 in the direction of the arrow in Fig. 1 the concaved faces 15 of the shoes 14 in engagement with the rollers act to force the latter toward the shallow ends of the pockets, incident to the springs 18 acting upon the 15 shoes. Thus, the rollers are positively actuated to bind between the shallow ends of the pockets and the periphery of the plate 20 so as to effect a quick and effective connection between the driving and driven 20 members of the clutch or ratchet mechanism.

I claim:

In a ratchet mechanism, a driving member embodying a disk, an annular flange formed on the periphery of said disk and provided 25 with a series of apertures spaced apart about the annulus and arranged at an angle thereto, an annulus within said flange and having

the inner face thereof formed with a series of pockets having inclined lower walls terminating in abrupt shoulders, said annulus 30 being formed with bores alining with the apertures in said flange respectively and communicating with said pockets, angularly disposed shoes within said bores having the inner ends thereof concaved, plugs within 35 said apertures, springs interposed between the confronting ends of said plugs and shoes and acting to force the latter into the pockets, a driven member comprising a circular plate disposed within said annulus, and rollers 40 within said pockets seated against the concave extremities of the respective shoes whereby the rollers are forced into frictional engagement with the shallow ends of said pockets and the periphery of said circular 45 plate when the driven member is rotated in one direction.

In testimony whereof I affix my signature in presence of two witnesses.

JOHN T. HUCK.
